DESIGN FOR A GOLF BALL OR THE LIKE

Frank H. Cavignac, New York, N. Y.

Application November 18, 1937, Serial No. 72,996

Term of patent 14 years

To all whom it may concern:

Be it known that I, Frank H. Cavignac, a citizen of the United States of America and resident of New York city, county of Queens, and State of New York, have invented a new, original, and ornamental Design for Golf Balls or the like, of which the following is a specification, reference being had to the accompanying drawing, forming part thereof.

In the drawing:

Figure 1 is an elevational view of a golf ball embodying the invention.

Figure 2 is an elevational view of the golf ball shown in Figure 1 after the same has been rotated through approximately 45° in a horizontal plane.

Figure 3 is a fragmentary sectional view taken along the plane 3—3 of Figure 2.

I claim:

The ornamental design for a golf ball or the like as shown.

FRANK H. CAVIGNAC.
